(57) **CLAIM**

I claim the ornamental design for a measurement jig, as shown and described.

DESCRIPTION

FIG. 1 is a perspective view observed from top thereof;
FIG. 2 is a perspective view observed from bottom thereof;
FIG. 3 is a top view thereof;
FIG. 4 is a bottom view thereof;
FIG. 5 is a front view thereof;
FIG. 6 is a right side view thereof; and,
FIG. 7 is a cross-section view taken along the line 7-7 of FIG. 3.

1 Claim, 3 Drawing Sheets
